[57] CLAIM

The ornamental design for a toy chipmunk animal figure, as shown and described.

DESCRIPTION

FIG. 1 is a front perspective view of a toy chipmunk animal figure showing my new design;

FIG. 2 is a top plan view;

FIG. 3 is a left side view;

FIG. 4 is a front elevation;

FIG. 5 is a rear elevation;

FIG. 6 is a bottom plan view; and

FIG. 7 is a bottom plan view of an alternative embodiment, the other views being shown in FIGS. 1-5.
